UNITED STATES PATENT OFFICE.

HUGH A. BARDEEN, OF HOLLYWOOD, CALIFORNIA, ASSIGNOR OF ONE-FOURTH TO HARLAN G. PALMER AND ONE-HALF TO JAY E. RANDALL, BOTH OF LOS ANGELES, CALIFORNIA.

WELL-TOOL.

1,132,062.

Specification of Letters Patent. Patented Mar. 16, 1915.

Application filed January 6, 1913. Serial No. 740,555.

To all whom it may concern:

Be it known that I, HUGH A. BARDEEN, a citizen of the United States, residing at Hollywood, in the county of Los Angeles 5 and State of California, have invented a new and useful Well-Tool, of which the following is a specification.

In drilling oil wells it frequently happens that water is encountered in some of the 10 strata drilled through before the oil sand is reached, and it is necessary before the well is completed to shut off the water so that the same cannot flow downwardly into the oil sand and become mixed with the oil taken 15 from the well. Several methods have been employed for accomplishing this purpose, and it is a common method to place cement between the casing and the wall of the well. In hard formations this method may last for 20 a short time, but in many cases where the walls of the well consist of clay or other soft material, as the oil is pumped from the bottom of the well the pressure on the lower side of the cement is reduced and 25 water seeps downwardly around the cement, eventually forming passages around the cement, in which case the water finds its way to the oil sand and mixes with the oil.

The main object of my invention is to provide 30 a tool by means of which circular recesses may be cut in the wall of the well, which recesses extend outwardly into the formation a considerable distance. The recesses so formed are filled with cement there- 35 by forming a collar of cement about the well casing which extends outwardly into the formation a sufficient distance to prevent any appreciable amount of seepage of water about the same.

40 Another object of my invention is to produce a tool of the character described of simple form and construction and of simple operation.

Referring to the drawings, which are for 45 illustrative purposes only: Figure 1 is a vertical sectional view of the lower portion of an oil well showing a tool therein embodying a form of my invention. Fig. 2 is a vertical sectional view of the tool shown in 50 Fig. 1. Fig. 3 is a sectional view on line c^3-c^3 Fig. 2. Fig. 4 is a perspective view of the head which forms a part of the tool. Fig. 5 is a perspective view of one of the cutters, and Fig. 6 is an end view of one 55 of the cutters.

I have illustrated my invention as applied in connection with rotary drilling tools for drilling a well, the wall of the well being indicated at 1 and the bottom of the well indicated at 2, as shown in Fig. 1.

3 indicates a cutting shoe secured to the lower section 4 of a drill pipe. Connected to the upper end of the section 4 of the drill pipe by means of a collar 5 is the body member 6 of the tool. Extending downwardly thereinto from the upper end of the body member 6 is a rectangular opening or recess 8 which extends nearly to the bottom of the body member 6, the bottom of the body member 6 being closed by a wall 7.

10 designates a head of a general rectangular form in cross section, which head is 70 slidably in the opening 8 in the body member 6. The head 10 is cut away at each corner, as indicated at 11, to receive longitudinally extending ribs 12 which extend into the opening 8 of the body member 6 from the corners thereof. The upper end of the head 10 terminates in a cap 14 which is exteriorly threaded to engage within the lower 75 end of the upper section of drill pipe 15, which drill pipe 15 extends upwardly to the exterior of the well.

Formed on the head 10 and extending 80 downwardly therefrom is a rod 16 which extends through the wall 7 in the lower end of the body member 6 through packing 17 therein and packing follower 18. The lower end of the rod 16 is threaded and provided with lock nuts 20. These lock nuts may 85 be secured at various points on the rod 16 to adjust the amount of travel of that rod. The opposite faces of the head 10 are cut away, as indicated at 21, which cut away portions terminate in diagonally arranged 90 guides 22, each of which is provided with a dove-tail groove 24, the guides 22 and the grooves 24 therein being reversely arranged 95 on the opposite sides of the head 10.

The body member 6 is provided with two 100 lateral openings 26 parallel with the opposite faces of the head 10. Slidably mounted in each opening 26 is a cutter or blade 28, the inner end of each cutter or blade being provided with a dove-tail 29 adapted to engage 105 the respective dove-tail grooves 24 in the face of the head 10. The outer end of each cutter 28 is provided with a cutting edge 30, the outer ends of the cutters conforming in general lines to the rounded 110

exterior of the body member 6. The lower edge 32 of each cutter 28 is beveled, as shown in Fig. 6, for the purposes herein-after described. The head 10 is provided 5 with a bore 33 which extends downwardly through the head and the rod 16 thereon, the bore 33 being provided for the purpose of delivering water from the interior of the drill pipe to the cutting shoe for the pur-
10 pose of performing the usual bailing opera-tion of the well during the cutting opera-tion.

The operation is as follows: After the well has been drilled to approximately the point 15 where it is desired to perform the cementing operation, the tool is mounted in the drill pipe, as shown. The lower section 4 of the drill pipe is of sufficient length so that the cutting shoe 3 rests upon the bottom of the well 2, the parts of the tool, as the drill pipe carrying the tool reaches the bottom of the well, assuming the position shown in Fig. 2, in which position the weight of the drill pipe is carried by head 10 which is pre-
20 vented from moving downwardly by the cutters 28, the cutting faces 30 of which contact with the wall of the well. As the drill pipe is rotated in the usual manner of rotating drill pipes with a rotary rig, the weight of
25 the casing on the head 10 causes the cutters 28 to be moved laterally through the open-
ings 26 in the body member 6, due to the fact that the inclined guides and the walls of the dovetail grooves 24 on the head 10 engage
30 the inclined inner ends of the cutters 28. As the wall of the well is cut away by the cutting edge 30 of the cutters 28, the head moves downwardly until the cutters have reached their extended position shown in dot
35 and dash lines Fig. 2 and in full lines in Fig. 1, at which time the cap 14 on the upper end of the head 10 is resting against the upper face of the body member 6, as indicated in dot and dash lines Fig. 2.
40 45 If it is desired, the tool may be withdrawn as soon as the above operation has been ac-complished, the result being a circular open-ing or recess 42 cut in the wall of the well having the same depth as the cutters 28 and
50 extending into the wall of the well a distance equal to the extended position of the cutting faces 30 of the cutters 28; but if it is desired to increase the depth of the recess in the well wall, the rotative movement of the
55 drill pipe is continued, and as the weight of the drill pipe 15 is transmitted through the body member 6 and the lower section 4 of the drill pipe, the cutting shoe 3 commences to drill the well to a greater depth. As the
60 cutting shoe cuts downwardly into the bot-tom of the well, the beveled lower face 32 of the cutters 28 cuts the opening in the wall of the well to a greater depth, as indicated in Fig. 1, the downward movement of the cut-
65 ters 28 and the cutting shoe 3 being the same.

When the recess or opening 42 has been made of sufficient depth, the tool is removed from the well in the following manner. The drill pipe 15 is pulled upwardly causing the head 10 to slide or move vertically in the 70 body member 6, which retracts the cutters 18 into the position shown in Figs. 2 and 3 caused by the engagement of the dove-tails 29 on the cutters with the inclined dove-tail grooves 24 on the head 10. When the 75 cutters have assumed the position indicated in Figs. 2 and 3, the continued upper move-
ment of the drill pipe 15 lifts the body mem-ber 6 and the lower section 4 of the drill pipe by means of the nuts 20 on the rod 16 80 engaging the under face of the packing fol-lower 18.

As shown in Fig. 1, several openings or re-cesses may be made in the well wall, in which case the upper recess is first made, after 85 which the tool is withdrawn from the well, as heretofore described, and a shorter section of drill pipe inserted for the section 4 shown, after which the same operation is repeated 90 for cutting the lower recess as is performed 95 in cutting the upper one. After the recesses have been cut in the wall of the well, cement is thrown into the bottom of the well in any preferred manner, which cement fills the well to a point above the highest recess and 95 extending into and filling the recesses 42. Before the cement has become set, the well casing, not shown, is forced downwardly through the cement to the bottom of the well, leaving cement between the casing and wall 100 of the well which has collars or extended bodies of cement around the casing at each recess, after which the cement within the well casing is drilled out or removed and the operation of drilling the well continued 105 into the oil sand.

What I claim is:—

1. A well tool comprising a body member, a head slidably mounted in said body mem-ber, said body member having a lateral 110 opening in each side thereof, a cutter in each opening, slideable engaging means be-tween said cutters and said head adapted to expand and retract said cutters, a cap on said head adapted to engage the upper end of 115 said body member, a rod on said head ex-tending downwardly through the bottom of said body member, and means on the lower end of said rod for limiting the upward movement of said head, relative to the body 120 member.

2. A well tool comprising a body member, having a lateral opening in the opposite sides thereof, a head slidably extending into the upper end of said body member, a dia-gonally arranged wall on the opposite sides of 125 said head, each having a dove-tail groove therein, said walls being reversely inclined with relation to each other, a cutter in each lateral opening in said body member, a dove- 130

tail on the inner end of each cutter, and a means whereby said head may be raised and lowered in said body member.

3. A well tool comprising a body member having a lateral opening in the opposite sides thereof, a head slidably extending into the upper end of said body member, a diagonally arranged wall on the opposite sides of said head, each having a dove-tail groove therein, said walls being reversely inclined with relation to each other, a cutter in each lateral opening in said body member, a dove-tail on the inner end of each cutter, a cap on the upper end of said head adapted to engage the upper end of said body member, a rod on the lower end of said head extending through the bottom of said body member, and means on said rod for limiting the upward movement of said head in said body member.

4. In combination with a drill pipe, a tool comprising a body member having a lateral opening in the opposite sides thereof, a cutter in each opening, a head slidably mounted in said body member, a cap on the upper end of said head secured to the lower end of said drill pipe, said cap being adapted to engage the upper end of said body member, a rod on the lower end of said head extending through the bottom of said body member, means on said rod for limiting the upward movement of said head, means on the lower end of said body member for supporting the same, and means for slidably engaging said cutters with said head for expanding and retracting said cutters.

5. In combination with a drill pipe, a tool comprising a body member having a lateral opening in the opposite sides thereof, a cutter slidably mounted in each opening, a head slidably mounted in said body member, means for preventing relative turning movement between said head and said body member, a cap on the upper end of said head secured to the lower end of said drill pipe, said cap being adapted to engage the upper end of said body member, means on said head for engaging said body member for limiting the upward movement of said head in said body member, a section of pipe secured to the lower end of said body member, a cutting shoe on the lower end of said section of pipe, and means for slidably engaging said cutters with said head for expanding and retracting said cutters.

6. A well tool comprising a head, a body member slidably mounted on said head and

having lateral openings in the sides thereof, a cutter in each opening in said body member, means on said head for expanding and retracting said cutters, and a rod on said head extending downwardly through the bottom of said body member and provided with adjusting means for limiting the travel of said body member on said rod.

7. A well tool comprising a pipe, a head fastened to said pipe, a body member slideable on said head and having lateral openings in the sides thereof, diagonally arranged walls on the opposite sides of said head each having a dove tail groove therein, said walls being reversely inclined with relation to each other, and a cutter in each lateral opening in the said body member, each cutter having a dovetailed opening engaging the grooves in said head.

8. A well tool comprising a pipe, a head rigidly secured to said pipe, a body member slideable on said head and having lateral openings in the sides thereof, diagonally arranged walls on the opposite sides of said head each having a dovetail groove therein, said walls being reversely inclined with relation to each other, a cutter in each lateral opening in said body member, each cutter having a dovetailed opening engaging the grooves in said head, and a rod on said head extending downwardly through the bottom of said body member and provided with adjusting means for limiting the travel of said body member on said rod.

9. A well tool comprising a pipe, a head rigidly secured to said pipe, a body member slideably mounted on said pipe, cutters adapted to be expanded and retracted by said head, and a cutting member rigidly attached to said body member and having a recess therein, said head extending into said recess and having a passage for conducting water into said recess.

10. A well tool comprising a body member having vertical slots therein these slots being parallel with the axis of the well, cutters carried by these slots, said cutters being moved in a line at right angles to said axis, and means for adjusting the distance said cutters may be moved.

In testimony whereof, I have hereunto set my hand at Los Angeles, California, this 7th day of December, 1912.

HUGH A. BARDEEN.
